AMALGAM PREPARING AND CARRYING MEANS FOR DENTAL PURPOSES

Marcus Clayton, 2 Endersleigh Gardens, Watford Way, Hendon, London NW. 4, England

Filed Apr. 28, 1958, Ser. No. 731,249

Claims priority, application Great Britain Feb. 14, 1958

7 Claims. (Cl. 32—60)

This invention relates to amalgam carriers for dental purposes.

In accordance with the invention there is provided an amalgam carrier for dental purposes, comprising an elongated body member having an abutment part at the front end thereof and having an ejection head at the rear end thereof, the ejection head including a tubular element which has an open end directed toward the abutment part and which is adapted to hold a charge of dental amalgam, the tubular element being provided with a ram displaceable within the tubular element by means operated from the front end portion of the carrier, the arrangement being such that the head can be located adjacent a cavity at the rear of a tooth and the ram operated from the front of the mouth so that, when the tubular element is charged with amalgam, the latter can be ejected forwardly into the cavity of the tooth.

For a better understanding of the invention and to show how it may be carried into effect, an embodiment thereof, given by way of example, will now be described with reference to the accompanying drawing, in which:

Figure 1 is a longitudinal sectional view showing an amalgam carrying instrument,

Figure 2 is a corresponding end view and

Figure 3 is a perspective view of an amalgam preparing device.

Referring to Figure 1, the amalgam-carrying instrument comprises an elongated body in the form of a tubular member indicated generally at 1 and including a tube 2 internally screw-threaded at one end for the reception of a shouldered ferrule 3 which is secured as by solder to the front end of a tubular extension 4, the ferrule being adapted when screwed into the tube 2, to hold the extension 4 removably in position in coaxial relationship with the tube 2. The tubular extension 4, the internal diameter of which is smaller than the internal diameter of the tube 2, terminates at its free end in an ejection head comprising a laterally projecting arm 5 which supports a tubular ejection element 6 substantially parallel with the extension 4 and having an open end 7 directed forwardly towards the tube 2. Within the tubular element 6 there is slidable a ram 8 formed integrally with a cross-part 9 which is generally parallel to the lateral arm 5 and which extends from the rear end of a rod 10 slidable in the tubular extension 4. The forward end portion of the rod 10 projects into the tube 2 and is fixed to actuating means comprising a plunger 11 having a free sliding fit within the tube 2. A sleeve 12 is slidably mounted on the tube 2, the sleeve having at its forward end a generally elliptical actuating plate 13 and being effectively connected to the internal plunger 11 by means of a retaining screw 14 which passes diametrically through the plunger and is displaceable, during axial sliding movement of the sleeve 12 relatively to the tube 2, along elongated holes or slots 18 at opposite sides of the tube 2, the head of the retaining screw engaging in a counter-sunk hole at one side of the sleeve 12, and the other end of the screw engaging in a screw-threaded hole at the opposite side of

2

the sleeve. At the end of the elongated member 1 remote from the ejection head, there is provided an abutment part comprising a pressure-plate 16 similar in shape to the plate 13, the plate 16 being carried by a plug 15 which is screwed into the front end of the tube 2. Between the plug 15 and the plunger 11 there is disposed in the tube 2, a compression spring 17 adapted to maintain the plunger 11 and the rod 10 in a normal inoperative or retracted position in which the retaining screw 14 engages the rear ends of the elongated holes 18 and in which the ram 8 is located in a retracted position, indicated by chain-dotted lines, to provide a space at the front end of the tubular element 6 for the reception of a charge of amalgam. The length of the holes or slots 18 determines the limits of movement of the plunger and sleeve, for displacing the ram from the retracted position into a fully projected forward position.

The arrangement is such that after charging the operating head with amalgam, the instrument can be inserted into the mouth of the patient and the tubular element 6 located in position in register with a cavity at the rear of a tooth. With the instrument gripped in the hand so that the pressure plate 16 is held against the palm of the hand, the actuating plate 13 can be gripped by the fingers and pulled forwardly so as to displace the rod 10 and the ram 8 against the action of the spring 17, thereby to eject the amalgam from the tubular element 6 into the cavity. Thus, the instrument is particularly convenient for use in the filling of cavities at the rear of molar teeth and avoids submitting the patient to discomfort as by undue distortion of the lips and cheeks. Upon release of the plate 13, the spring 17 returns the plunger 11 and the rod 10 into the retracted position so that the front end portion of the tubular element 6 can be recharged with amalgam when the instrument is next used for a tooth filling operation.

To facilitate the charging of the instrument with amalgam, there is provided a device consisting of a mortar 19 formed with a rounded cavity 20 in which the ingredients of the amalgam may be ground and mixed. The mortar device 19 is formed at diametrical opposite sides with recesses 21 each providing a shelf onto which the prepared amalgam can be displaced from the cavity 20. The recesses open into the upper rim or edge of the mouth of the device 19 so that the tubular element 6 of the carrier instrument can readily be positioned in a recess as illustrated diagrammatically in Figure 3 for charging with amalgam. It will be appreciated that the recesses 21 may be of an appropriate shape according to the form of the ejection head of the instrument. If desired, the recesses may be replaced by an annular groove or recess extending completely around the rim of the mortar device and communicating with the interior of the device.

55 I claim:

1. An amalgam carrier for dental purposes, comprising a tubular member, an abutment part at one end of said tubular member, an ejection head at the end of said tubular member remote from said abutment part, said ejection head including an ejection tube disposed at one side of and fixedly secured to said tubular member, said ejection tube being parallel to said tubular member and having an open front end directed towards said abutment part, an ejection ram slidably in said ejection tube, a rod movable axially within said tubular member and rigidly connected at one end to said ram, and actuating means operatively connected to the opposite end of said rod for moving said rod to displace the ram forwardly for ejection of amalgam from the open end of said ejection tube.

60 2. An amalgam carrier for dental purposes, comprising a tubular member, an abutment part at one end of

said tubular member, an ejection head at the end of said tubular member remote from said abutment part, said ejection head including an ejection tube disposed at one side of and generally parallel to said tubular member, said ejection tube having an open front end directed toward said abutment part, and an ejection ram slideable in said ejection tube, said carrier comprising also a rod slideable axially in said tubular member and having at one end thereof a rigid connection with said ejection ram, spring means acting on and urging said rod into a normal retracted position to hold the ram in a position removed from the open front end of said ejection tube, and actuating means operatively connected to said rod at the end thereof remote from said ram, said actuating means being operable to pull the rod against the action of said spring means and displace the ram to eject amalgam forwardly from the open end of the ejection tube.

3. An amalgam carrier for dental purposes, comprising a tubular member, an abutment part at one end of said tubular member, an ejection head at the end of said tubular member remote from said abutment part, said ejection head including an ejection tube disposed at one side of and generally parallel to said tubular member, an arm projecting laterally from said tubular member and carrying said ejection tube, the latter having an open front end remote from and directed toward said abutment part, an ejection ram slideable in said ejection tube, an operating rod slideable axially in said tubular member, and having at one end thereof a laterally projecting portion substantially parallel to said arm and forming an integral rigid connection between said operating rod and said ram, spring means acting on and urging said rod into a normal retracted position to hold the ram in a position removed from the open front end of said ejection tube, and actuating means operatively connected to said rod at the end thereof remote from said laterally projecting portion, said actuating means being operable to pull the rod against the action of said spring means and displace the ram to eject amalgam forwardly from the open end of the ejection tube.

4. An amalgam carrier for dental purposes, comprising an elongated body member having an abutment part at one end thereof and an ejection head at the opposite end thereof, said ejection head including an ejection tube fixedly mounted at one side of and parallel to said elongated body member, said ejection tube having an open front end directed towards said abutment part, an ejection ram slideable in said ejection tube, and means operable from said one end of said elongated body member for actuating said ram to eject amalgam from the open end of said ejection tube, said actuating means comprising an element displaceable axially of said elongated body member and having a portion which, at said oppo-

site end of said elongated body member, extends laterally and forms an integral rigid connection between said element and said ram.

5. An amalgam carrier, comprising a tubular member carrying, at its front end, an abutment part in the form of a pressure plate and, at its rear end, an ejection head including an ejection tube mounted at one side of and parallel to said tubular member, said ejection tube having an open end directed forwardly towards said pressure plate, an ejection ram slideable in said ejection tube, and means operable from the front end portion of said tubular member for actuating said ram to eject amalgam forwardly from the open end of said ejection tube, said actuating means comprising a plunger slideable axially in said tubular member, a rod fixed to and extending rearwardly from said plunger for axial sliding movement in said tubular member, said rod having at its rear end a laterally extending portion which forms an integral rigid connection with said ram, a sleeve slideable along the exterior of said tubular member and operatively connected to said plunger, and a finger grip on said sleeve by which said sleeve together with the plunger and associated rod can be pulled axially forwardly from a normal retracted position toward said pressure plate during an ejection operation.

25 6. An amalgam carrier as claimed in claim 5, wherein said sleeve is operatively connected to said plunger by means including a screw extending diametrically through said sleeve and plunger and having portions slideable, during axial movement of said plunger, along diametrically opposite axial slots formed in said tubular member, the rear ends of said slots forming abutments engaged by said screw in the retracted position of said rod and ejection ram, and the front ends of said slots forming abutments engageable by said screw to limit the forward axial movement of said rod and ejection ram during an ejection operation.

30 7. An amalgam carrier as claimed in claim 5, including a compression spring located in said tubular member between said plunger and the pressure plate at the front end of said tubular member, said spring urging said plunger axially rearwardly to return said rod and ejection ram into the normal retracted position thereof after each ejection operation.
